UNITED STATES PATENT OFFICE.

JOHN W. JACKSON, OF AUGUSTA, GEORGIA.

ROTARY KITCHEN CABINET.

Application filed December 21, 1922. Serial No. 608,221.

To all whom it may concern:

Be it known that I, JOHN W. JACKSON, a citizen of the United States of America, and a resident of Augusta, Georgia, have invented certain new and useful Improvements in Rotary Kitchen Cabinets, of which the following is a specification.

This invention is an improvement in cabinets, known generally as "kitchen cabinets," and one of the principal objects thereof is to provide a cabinet which is small and compact enough to conveniently occupy a place in small apartments, dining cars, boats, and small kitchens.

Another object of the invention, considered from a structural view-point, is to provide an improved cabinet in which the various materials and provisions used in the preparation of meals may be stored away in receptacles arranged and mounted in circular form upon a rotatable axis, so that various receptacles can be brought into convenient access to the person using the cabinet, as he may desire to use the contents of such receptacle, without the necessity of the person moving about, or reaching high or awkwardly accessible places.

Another object of the invention is to provide a cabinet having rotatably mounted receptacles, and having doors or closures on which retainers for various articles used in the preparation of meals, may be placed or hung.

Another object of the invention is to provide a cabinet in which, with respect to certain of the receptacles, access may be had to these receptacles for the purpose of filling them or removing material from them, without opening the cabinet up, in case it is desired to keep it closed, this object being attained by providing a door at the top of the cabinet with which the upper tier of receptacles may be brought into registration.

A further object of the invention is to provide a cabinet of the type disclosed, which is economical of manufacture, readily assembled, and easily accessible for adjustment, replacements or repair.

With these and other objects in view, which will become more apparent as the description proceeds, the invention resides in the construction, combination, and arrangement of parts hereinafter more fully described and claimed, and illustrated in the accompanying drawings in which,—

Figure 1 represents a view in perspec-

tive of a cabinet constructed in accordance with my invention.

Figure 2 represents a similar view looking at the cabinet from another side. 60

Figure 3 represents a horizontal sectional view on the line 3—3 of Figure 4.

Figure 4 represents a vertical sectional view through the cabinet.

Figure 5 represents a horizontal sectional view on the line 5—5 of Figure 4. 65

Figure 6 represents a fragmentary bottom plan view, and

Figure 7 represents a detailed sectional view on the line 7—7 of Figure 4. 70

Figures 8 and 9 represent respectively, diagrammatic modifications of the arrangement of receptacles and partitions of the lower tier of receptacles.

Referring more particularly to the drawings, it will be noted by reference to Figures 1 and 2, that the cabinet is preferably made rectangular in shape, the doors being placed on two adjacent sides of the cabinet, so that the cabinet can be conveniently placed in a corner with the remaining two sides of the cabinet close to the intersecting walls of the room or space occupied by the cabinet. 75

The sides and doors of the cabinet may readily be made of sheet metal. The receptacles may likewise be made of sheet metal. This material lends itself readily to fabrication, is economical, and may be readily finished with enamel, or other materials. The top also may be made of sheet metal, or of cast metal, or wood, either alone or covered with any desired material. 80

The sides 1 and 2 of the cabinet are preferably uninterrupted, while the remaining sides 3 and 4 are occupied by doors, as will appear in detail later. 85

At the upper edges of the sides 1, 2 and 4, and on the inner surfaces thereof, extends a strip 5, which braces the cabinet at its upper portion, and to which the top 6 may be secured. The top is preferably removable, and may be retained in place by means of screws 7 extending through the top and into the strips 5. Other securing devices may be used if desired. 90

The legs of the cabinet may be formed integrally with the material which forms the sides, by so cutting the material that at the corners of the cabinet downwardly extending flaps are left, the edges of which may be folded in as indicated at 8 (see Figure 6), and thus form rigid supports. 100

The lower portion of the cabinet may be strengthened by means of crossed braces 9, which extend between opposite corners of the cabinet and which cross at a central point. These cross braces may be made of wood or other material, and may rest upon the upper edges of the legs of the cabinet, the portions 8 being folded in below the braces. The parts of the material forming the sides above the inturned portions 8, may be bent in against the braces 9 as at 10, and secured in any suitable manner to the braces, for additionally supporting the braces and rigidifying the cabinet. The braces, in addition to strengthening the cabinet, may serve as a means for supporting the rotary receptacle container.

This container includes a bottom disk or plate 11, and an intermediate disk or plate 12. A vertical shaft 13 extends through the centers of the disks, and the lower disk may be supported on an enlargement or shoulder 14 carried by the shaft. A sleeve 15 interposed between the lower and intermediate disks, and encircling the shaft, may support the intermediate disk 12. At its lower end, the shaft may have a bearing (of suitable type) indicated at 16, in the crossed braces 9, while the upper end of the shaft may have a bearing (of suitable type), indicated at 17, in the cover or top 6 of the cabinet.

The upper tier of receptacles 18, are substantially wedge-shaped in general outline, tapering from their outer portions towards the center of the tier, and are mounted upon the intermediate disk 12, being retained in place thereon by an up-turned flange 19 at the periphery of the disk. The upper receptacles are so proportioned as to just fill the area they are intended to occupy, so that they are readily held in place by a wedging action against each other, and by being engaged at their outer ends by the up-turned flange 19. This construction allows of any of the receptacles being readily removed when desired for cleaning or repair. Each of the upper receptacles 18 is provided with a hinged cover 20 which may be provided with a handle as shown. The top 6 of the cabinet is provided with a door 21, and the relationship of the door-opening, and the dimensions of the upper tier of receptacles is such that when the receptacle support is rotated, the upper receptacles will successively come into registration with the door-openings. Hence, in order to obtain access to the upper receptacles, the door 21 in the top may be raised, and the desired receptacle brought into register with the door-opening, and its cover raised, as indicated in Figure 1. This construction allows for access to the upper receptacles without the necessity of opening the side doors of the cabinet.

The lower tier or series of receptacles is

in the shape of alternately slidable and pivoted receptacles 22, and 23, the slidable receptacles being in the form of drawers open at their top, while the pivoted receptacles are substantially tri-angular in shape, and are also open at the top. The spaces for receiving the lower receptacles are defined by a pair of parallel transverse partitions 24 extending between the disks 11 and 12, and preferably equi-distant from the shaft 13, and at right angles to which and extending from them toward the periphery of the disks are shorter partitions 25. The space between the long partitions 24 may be occupied by oppositely arranged drawers of considerable length, the spaces between the shorter partitions 25 being occupied by drawers of less length. The remaining triangular spaces are occupied by the hinged receptacles 23, the hinge pintles 26 thereof extending between the upper and lower disks. These pintles may engage into openings in the lower disk 11, and may be headed at their upper ends, the heads being countersunk into the intermediate disk 12, so that the pintles may thus be readily removable when it is desired to remove the hinged receptacles 23. This structure is indicated in dotted lines in Figure 4. The slidable receptacles 22, and the hinged receptacles may be provided with handles 27, to afford means for conveniently rotating the receptacles, and for withdrawing them when it is desired to have access to them.

The side 3 of the cabinet is occupied by a single door 28, and a double door 29. These doors may readily be made of sheet material of the same type of which the sides of the cabinet may be formed. The door 28 may be hinged at its outer edge to the side of the cabinet adjacent one corner as indicated at 30, the hinges being formed by forming registering eyes in the material at the meeting edges of the door, and the side, and by dropping a suitable pintle through these eyes. The hinges for the other doors which are hinged to the sides of the cabinet may be formed in the same manner. Likewise, the two sections of the double door 29 may be hinged together by forming registering eyes of the material at the meeting edges of the doors, and dropping a pintle through these eyes. The doors just described are so proportioned as to completely enclose the side 3 when they are folded in, and the single door 28, and the outer member of the double door are preferably proportioned to overlap. Turn buttons, or other suitable devices 31 may be used for locking the doors in closed position.

Arranged on the door 28 is a series of substantially triangular shelves 32 for the reception of articles, and on the inner member of the double door may be arranged a series of racks 33 for the reception of cloths

- or spoons, or other utensils. On the outer member of the door a towel rack 34 may be mounted. The shelves 32 are so proportioned in breadth that clearance will be provided between the rotary receptacles and the corner adjacent which the door 28 is hinged, so that the shelves may, when the door is closed, readily pass in between the corner and the receptacles, and conveniently occupy that space, as indicated in Figure 5. Likewise, the racks 33, as indicated in Figure 3, will occupy a space between the rotary receptacles and the side of the cabinet formed by the double door when this door is closed.
- 15 The towel rack 34, as indicated in Figure 4, may occupy a space just above the upper tier of receptacles 18. It is to be noted that these receptacles slope downwardly slightly at their tops and toward their outer ends, 20 for the purpose of making their interiors easily accessible when their lids 20 are raised. A portion of the space thus formed may be occupied by the rack 34.
- 25 A bread-board 35 is slidably retained in guides 36 on the under side of the top 6 (see Figure 7 for detail). This board may occupy a portion of the space between the top and the upper series of receptacles, and may be easily accessible by opening the 30 door 28.
- 30 The side 4 of the cabinet is occupied by a pair of doors 37 and 38, respectively hinged at their outer edges to adjacent corners of the cabinet, in the manner already described, 35 and preferably overlapping at their inner edges when in closed position. On the inner sides of these doors may be mounted substantially triangular shelves of somewhat greater depth than the shelves 32, indicated 40 at 39 and 40, respectively. The shelves 39 may have solid walls and bottoms, while the shelves 40 may be of wire mesh, or other material. These shelves are so proportioned as to readily occupy the spaces between 45 the corners to which the doors 37 and 38 are hinged, and the rotary receptacles, as indicated in Figure 5. They are so proportioned, of course, as to clear the rotary receptacles when the doors are closed or 50 opened.
- 50 The sheets of material from which the sides are fabricated may, at the corner opposite which the doors 29 and 37 are hinged, overlap as at 41, and a vertical member 42 may, at this corner, extend between the cross brace 9 at the bottom, and the strip 5 at the top, for the purpose of affording a means whereto the overlapped edges may be connected, and further to additionally 55 strengthen the structure.
- 60 In manufacturing the cabinet, the sides and strengthening supports and frame-work may be formed and secured together, then the structure composing the rotary contain- 65 ers may be assembled, and this unit placed bodily within the cabinet. The doors with their attached shelves and racks, may then be mounted, and then the top may be put in place, the shaft, of course being properly positioned in its bearings. This structure 70 allows of the cabinet being readily assembled, and also allows of easily disassembling it, so that parts may be removed for cleaning or replacement or repair.
- Instead of the arrangement of receptacles 75 and partitions in the lower tier, which has heretofore been described, I may, if desired, use either of the arrangements diagrammatically indicated in Figures 8 and 9, the construction of the lower tier of receptacles, 80 except for the arrangement shown in those figures, being the same as has already been described. In Figure 8, the receptacles are all in the shape of segments of a circle, being geometrically arranged with respect to 85 the center of the tier, and each being hinged. The receptacles are indicated at 23', and the hinged pins at 26'. The partitions 25' are also geometrically arranged with respect to the center, and occur one between each adjacent pair of receptacles. The arrangement in Figure 9 corresponds substantially with that shown in Figure 5, except that the shorter of the slidable receptacles 22 are eliminated, and the pivoted receptacles 23, 90 consequently elongated. The pivoted receptacles in this figure are indicated at 23'', the partitions arranged between the adjacent pivoted receptacles being indicated at 25''. 95
- 100 And I may also, if desired, attach shallow receptacles 43 on the legs of the cabinet near their lower ends, into which receptacles may be placed water to prevent ants, or other insects from getting into the cabinet.
- 105 In use, the cabinet may be used either alone, or if desired, a super-structure of shelves or cabinets may be mounted upon it. The foregoing detailed description has been given for clearness of understanding, and no undue limitations should be deduced therefrom, but the appended claims should be construed as broadly as permissible, in view of the prior art.
- 110 Having thus described my invention what I claim as new and desire to secure by Letters Patent is,—
- 115 1. A cabinet including a housing, a shaft revoluble and detachably mounted within the housing, a series of receptacles detachably supported upon the shaft, a top detachably mounted on the housing and forming a journal for the upper end of the shaft, a door arranged in the top in such position that the uppermost receptacles may be brought into registration therewith, and doors on the sides of the housing for affording access to others of the receptacles.
- 120 2. A series of revolvable receptacles for a cabinet including a shaft, spaced disks mounted thereon, a plurality of slidable and 125
- 130

hinged receptacles mounted between the disks, and a plurality of substantially wedge-shaped receptacles mounted upon the upper-most disk and occupying substantially 5 the entire area thereof, said upper-most disk having a flanged portion engaging the outer edges of the wedge-shaped receptacles for detachably retaining them in place.

3. A series of revoluble receptacles for a 10 cabinet including a shaft, a disk mounted thereon, a plurality of receptacles arranged on the disk and abutting against each other laterally, and co-operating means between the receptacles and the periphery of the disk 15 for detachably retaining the receptacles in place on the disk, preventing movement of the receptacles radially of the disk but allowing their removal axially of the disk.

4. A cabinet including sides formed of 20 sheet material, the material of the sides at the corner of the cabinet projecting downwardly and being inturned at the corners to provide supporting legs, braces resting upon the legs, and a series of receptacles mounted 25 upon the braces.

5. A cabinet including a disk rotatably mounted therein, a revoluble shaft on which the disk is mounted, a plurality of receptacles arranged on the disk and abutting 30 against each other laterally, co-operating means between the receptacles and the disk for detachably retaining the receptacles in place on the disk and preventing movement of the receptacles radially thereof, and a 35 removable top on the cabinet overlying the receptacles and allowing of their removal axially of the disk when the top is removed, said shaft being detachably journaled for

rotation and support at its upper end in said top.

6. A cabinet including a disk rotatably mounted thereon, a revoluble shaft on which the disk is mounted, a plurality of receptacles arranged on the disk and abutting against each other laterally, co-operating means 40 between the receptacles and the disk for detachably retaining the receptacles in place on the disk and preventing movement of the receptacles radially thereof, a removable top on the cabinet overlying the receptacles and allowing of their removal axially 45 of the disk when the top is removed, said shaft being detachably journaled for rotation and support in said top lids on the receptacles and a door on the top into registration with which the receptacles may be brought for allowing access to the receptacles without removing the top.

7. A cabinet including a housing, a shaft revolvably mounted therein, a lower disk carried by the shaft, an upper disk carried by the shaft, partitions arranged between the disks, a lower tier of receptacles arranged between the disks and partitions, and movable radially of said disks, an upper tier of 60 receptacles mounted upon the upper disk, a flange on the upper disk preventing movement of the upper tier of receptacles radially of said upper disk, and a removable top for the housing allowing removal of the upper tier of receptacles axially of the disk when the top is removed, said shaft being journaled for rotation and support in said top.

In testimony whereof I hereunto affix my signature.

JOHN W. JACKSON.
